UNITED STATES PATENT OFFICE.

HARRY DONALD TIEMANN, OF MADISON, WISCONSIN, AND NORMAN DE WITT BETTS, OF LINWOOD, UTAH, ASSIGNEES, BY MESNE ASSIGNMENTS, TO THE GOVERNMENT OF THE UNITED STATES AND TO THE PEOPLE OF THE UNITED STATES.

DRY-KILN.

1,276,451.

Specification of Letters Patent. Patented Aug. 20, 1918.

Application filed April 6, 1917. Serial No. 160,332.

(DEDICATED TO THE PUBLIC.)

To all whom it may concern:

Be it known that we, HARRY DONALD TIEMANN, a citizen of the United States of America, and an employee of the Department of Agriculture of the said United States, residing at Madison, in the county of Dane, State of Wisconsin, (whose post-office address is Madison, Wisconsin,) and NORMAN DE WITT BETTS, a citizen of the United States of America, and formerly an employee of the Department of Agriculture of the said United States, residing at Linwood, in the county of Uinta, State of Utah, (whose post-office address is Linwood, Utah,) have invented a new and useful Improvement in Dry-Kilns.

This application is made under the act of March 3, 1883, chapter 143 (22 Stat. 625), and the invention herein described and claimed may be used by the Government of the United States or any of its officers or employees in the prosecution of work for the Government or any person in the United States without payment to us of any royalty thereon.

Our invention relates to kilns for drying lumber or other moisture-bearing substances.

The object of our invention is to provide a dry kiln simple in construction and easy of operation, and one that will permit of uniform and rapid drying of lumber or other moisture-bearing substances, by means of superheated steam.

The features of our invention are (1) the method of securing the proper amount and direction of circulation, (2) the use of a much lower temperature of the superheated steam, and (3) the means of modifying the dryness of the medium in which the lumber is to be dried.

The object, characteristic features, and scope of our invention will be more readily understood from the following description taken in connection with the accompanying drawing wherein:

The figure is a transverse sectional view of our improved dry kiln.

Referring to the drawing, A represents the drying chamber which is inclosed by the walls, B, the roof, C, and the floor D. The floor should preferably drain toward the sides and there should be provision for

exhausting the excess steam to the air through the outlets, E. The recirculating flue, F, is separated from the drying room proper by partition, G. The heating device is shown at, H, and I, designates the steam inlet. The stack of lumber, J, is shown piled vertically and across the kiln, this being a convenient method of taking advantage of the full effect of the circulation, but other methods of piling known to the trade may be used.

By securing the heating device, H, to the side walls, B, and locating the steam jets, I, below the said heating device, as shown in the drawing, the steam supplied to the kiln through the jets, I, becomes superheated while in course of rising to the top of the kiln through the flue, F. This arrangement of the heating device, H, and steam jets, I, induces the escaping steam to pass rapidly through the recirculating flue, F, thereby producing a large circulation in the drying chamber. This method of heating the steam is preferable, but good results may also be obtained as to heating the steam in kilns where the heating pipes are located below the lumber by arranging the steam jets below such heating pipes thereby causing rapid vertical circulation of the superheated steam.

The invention applies to a series or battery of kilns as well as to the single chamber type.

In practising our invention, steam is admitted to the drying chamber, A, through the inlet, I, which should preferably consist of small openings on the side next to the heating device, H. This will produce a jet action and will cause a rapid circulation of steam up through the flue, F, and down through the lumber. The steam will, upon ascending through the flue, F, become superheated to a degree controlled by the adjustment between the amount of steam jetted into the kiln and the temperature of the heating device. On account of the superheated condition of the steam, drying of the lumber is possible, and the control of the amount of superheat allows the necessary control of the rate of drying. The action of the steam in giving a very fast circulation and at the same time acting as the drying

medium makes the operation of the kiln very simple. Furthermore, the nature of this drying medium, on account of its lack of oxygen, makes the possibility of fire in the kiln very remote and thus avoids an ever present danger to kilns using air at a high temperature.

From the foregoing, it is thought that the construction, operation and many advantages of the herein described invention will be apparent to those skilled in the art, without further description, and it will be understood that various changes in the size, shape, proportion, and minor details of construction may be resorted to without departing from the spirit or sacrificing any of the advantages of the invention.

Having thus described our invention, we claim:

- 20 1. A dry kiln including a drying chamber, a recirculating flue adjacent to a wall thereof, or some containing means for heating the circulating medium, and a steam inlet situated adjacent to the heating device so that the escaping steam will pass rapidly through the recirculating flue, thereby inducing a large circulation in the drying chamber and at the same time become superheated.
- 25 2. A dry kiln including a drying chamber, a heating device adjacent to a wall thereof, and an inlet for steam situated adjacent to the heating device so that the action of the steam in escaping will cause rapid circulation along the walls and through the drying chamber and at the same time permit the steam to be superheated.
- 30 3. A dry kiln including a drying chamber, a heating device adjacent to a wall thereof, and an inlet for steam situated adjacent to the heating device so that the action of the steam in escaping will cause rapid circulation along the walls and through the drying chamber and at the same time permit the steam to be superheated.

ber, a heating device adjacent to a wall thereof, and an inlet for steam situated adjacent to the heating device, so that the action of the escaping steam will cause rapid circulation through the lumber and at the same time the steam will become superheated by means of the heating device.

45

4. A dry kiln including a drying chamber, a heating device adjacent to a wall thereof, and an inlet for steam situated adjacent to the heating device so that the action of the escaping steam will cause rapid circulation through the lumber and at the same time the steam will become superheated by means of the heating device, and thus furnish a medium for drying the lumber that excludes the air necessary for combustion and therefore eliminates the possibility of fire during the drying process.

55

5. A dry kiln including a drying chamber, a heating device adjacent to a wall thereof, and an inlet for steam situated adjacent to the heating device, so that the action of the escaping steam will cause rapid circulation through the lumber and at the same time the steam will become superheated by means of the heating device.
